Primary Examiner — Richard Edgar*Assistant Examiner* — David Truong(57) **CLAIM**

The ornamental design for a beverage bottle as shown and described.

DESCRIPTION

Fig. 2.1 is a perspective view;

Fig. 2.2 is an exploded view;

Fig. 2.3 is a front view;

Fig. 2.4 is a right view;

Fig. 2.5 is a back view;

Fig. 2.6 is a bottom view; and

Fig. 2.7 is a top view.

The broken lines depict portions of the beverage bottle that form no part of the claimed design.
